UNITED STATES PATENT OFFICE.

FREDERICK J. GLEASON, OF WALPOLE, MASSACHUSETTS, ASSIGNOR TO STANDARD WOVEN FABRIC COMPANY, OF FRAMINGHAM, MASSACHUSETTS, A CORPORATION OF MASSACHUSETTS.

RUBBER HEEL.

1,188,347.

Specification of Letters Patent. Patented June 20, 1916.

Application filed April 23, 1915. Serial No. 23,490.

To all whom it may concern:

Be it known that I, FREDERICK J. GLEASON, a citizen of the United States, residing at Walpole, in the county of Norfolk 5 and State of Massachusetts, have invented certain new and useful Improvements in Rubber Heels, of which the following description, in connection with the accompanying drawings, is a specification, like 10 reference characters on the drawings indicating like parts in the several figures.

This invention relates to rubber heels and soles and other articles made of rubber (hereinafter, for convenience, referred to 15 as heels) and particularly to the friction plugs, or inserts, which now are commonly used in rubber heels, and to some extent in other articles.

It has been proposed heretofore to use 20 some friction metal, such for instance as lead, in plugs of this character but no satisfactory way has ever been found, so far as I am aware, of causing the metal to adhere to or bond with the other parts of the plug. 25 Consequently, in manufacturing heels having plugs containing metal inserts it has been necessary to rely upon some mechanical construction to lock the metal parts in the plug; but these constructions have 30 proved unsatisfactory for the reason that the metal parts become loose and drop out of the heel when it has been worn for only a relatively short time. The present invention has for an object the construction 35 of a heel having a plug containing friction metal but in which the metal will be bonded to the adjacent parts of the heel. The invention also is directed to the provision of a novel construction of friction plug which 40 may be advantageously used either with or without a friction metal, and which can be used generally in rubber articles in which a friction plug is desirable.

A convenient embodiment of the invention will now be described, reference being 45 made to the accompanying drawings, in which—

Figure 1 is a view of the tread face of a heel constructed in accordance with this invention; Fig. 2 is a cross-sectional view on 50 the line 2—2, Fig. 1; and Fig. 3 is a per-

spective view of a portion of the core of the friction plug of the heel shown in Figs. 1 and 2.

The heel shown in the drawings comprises a body 3 having a friction plug consisting of a core 4 and a jacket 5 for the core. The core is made up of strands or strips of friction metal 6, such for instance as lead, and strands or strips of some textile material, such as cotton, all these strands being twisted tightly together to form a rope of the cross-sectional dimensions required for the core 4. Preferably the rope is so twisted that the strands have a very sharp pitch. The rope is then wrapped tightly in a fabric such as duck or canvas to form the jacket 5 and the strip of material made up in this manner is cut transversely into pieces to form plugs of the required length. These plugs may then be flattened out if desired to give them the oval cross section shown in Fig. 1.

In the usual method of manufacture, the materials of which the core and jacket are 75 made are treated with a rubber cement, or compound, before being assembled so that all the parts of the heel will bond together during the vulcanizing operation. As previously stated, difficulty has been experienced in making the metal parts adhere to the adjacent parts of the heel; but I have found that if the strands or strips of lead or other metal used for this purpose are first coated with copper, either by electro-plating or otherwise, the copper reacts chemically during the vulcanizing operation with the adjacent parts of the heel to form a firm union or bond with these parts. In Fig. 3 the copper coating on the strands of lead 80 is indicated at 8. By this means, I am enabled to make a heel having a plug containing parts of friction metal and to effectively bond these metal parts to the other parts of the heel, thus overcoming the difficulty that heretofore has prevented the 85 satisfactory use of friction metal in rubber heels.

Preferably the area of metal exposed to wear on the tread face of the plug is approximately equal to the area of the textile material of the core exposed on this surface.

I prefer also to make the cross-sectional area of the jacket about equal to the cross sectional area of the body of the plug. The metal, of course, is worn away by abrasion 5 faster than the textile parts of the plug but the latter parts of the heel resist wear somewhat better than the rubber body of the heel. By proportioning the parts in substantially the manner described, an approximately uniform wearing surface is provided since the textile materials in the core and the jacket protect the ends of the metal strands from being gouged out or worn away materially faster than the surface of the rest of the plug. The plug preferably is inserted in the heel so that its axis lies substantially perpendicular to the tread face of the heel. The strands composing the core of the plug thus are caused to extend 10 transversely to the tread face of the heel so that the wear on the core comes on the ends of the strands.

The construction of plug shown is advantageous whether or not metal strands are used in the composition of the core since the twisting of the core in the manner described serves to interlock mechanically all the strands of the core with each other and the tight wrapping of these strands in the jacket 20 binds them together and prevents the strands around the edges of the core from becoming frayed out or torn away during the wear of the heel.

I consider it preferable to use the friction metal in strip form (although not necessarily in the specific form shown) rather than in the form of a large plug so as to present at the tread face of the plug a friction surface in which the metal and textile materials are well distributed; and also for the purpose of rendering the metal pieces less liable to displacement while the article is in use. It is obvious that the invention may take many forms and be used in many kinds of rubber articles where its friction or anti-slipping characteristics are desired, without departing from the spirit or scope of this invention.

I believe it to be new with me to use, in 50 a rubber article, a friction member containing metallic and non-metallic parts, the metallic part or parts being bonded to the parts adjacent thereto through the use of copper.

In my companion application Serial No. 55 62,619, filed November 20, 1915, for improvements in rubber articles, I have disclosed a construction that is in some respects an improvement on the construction disclosed in the present application. The 60 claims broad enough to cover both constructions are presented in the present application, and the claims of the later case are limited to subject-matter not disclosed in the present application.

Having thus described my invention, what I claim as new and desire to secure by Letters Patent of the United States is:—

1. A rubber heel having a friction plug vulcanized therein, said plug comprising a core including strands of friction metal 70 extending transversely to the tread face of the heel and a jacket of fabric encircling said core.

2. A rubber heel having a friction plug vulcanized therein, said plug comprising a 75 core consisting of strands of friction material extending transversely to the tread face of the heel and a jacket of fabric around said core.

3. A rubber heel having a friction plug 80 vulcanized therein, said plug comprising a core consisting of strands of friction material twisted together and extending diagonally to the tread face of the heel and layers of fabric encircling said core and binding 85 said strands together, said layers of fabric extending substantially perpendicular to the tread face of the heel.

4. A rubber heel having a friction plug vulcanized therein, said plug comprising 90 strands of textile material and friction metal twisted together to form a core, and fabric wound around said core.

5. A rubber heel having a friction plug vulcanized therein, said plug including 95 strands of textile material and friction metal extending transversely of the tread face of the plug, and said metal strands being bonded to the adjacent parts of the heel.

6. A rubber article having a tread face, 100 and a friction member vulcanized in said article and exposed to wear at said face, said member including strips of metallic and non-metallic materials interlocked with each other, and said metallic material including lead and having a coating of copper.

7. A rubber article having a tread face, 110 and a friction plug vulcanized in said article and exposed to wear at said face, said plug comprising strips of textile material and friction metal coated with copper, said strips being mechanically interlocked with each other.

8. A rubber article, having a friction member therein comprising textile material and 115 friction metal, said material and metal being in the form of strips bound together.

9. A rubber heel having a friction plug vulcanized therein, said plug including 120 strands of textile material and friction metal twisted together to form a core and layers of fabric wound around said core, said metal strands being bonded to the adjacent parts of the plug.

10. A rubber heel having a friction plug 125 vulcanized therein, said plug consisting of strands of cotton and lead coated with copper twisted tightly together to form a core

and cotton fabric wound around said core in a plurality of layers.

11. A rubber article having a friction member therein comprising friction metal and textile material, both in strip form, lying transversely to the face of the article exposed to wear and bonded to the adjacent parts of the article.

In testimony whereof I have affixed my signature, in presence of three witnesses.

FREDERICK J. GLEASON.
